Riding Saddle
Patented May 3, 1832.

George Pitchard, of Clarksburg, Va.
Letters Patent

The schedule referred to in these Letters Patent and making part of the same, containing a description in the words of the said George Pitchard himself of his improvement called the warm steel spring saddle.

To all to whom these presents shall come, George Pitchard of Clarksburg, in the County of Harrison, and State of Virginia, gentleman, sends greeting:

Be it known that I the said George Pitchard have invented, contrivled, made and applied to use a new and useful improvement in the mode of making Manufacturing Saddles, by the application of a steel spring to the seat of the saddle, called the warm steel spring saddle. This my said improvement in the mode of making Manufacturing Saddles (which I claim as my own invention which I believe was never before known or used till I invented the same) consists simply in the making of and applying to use in the seat of the saddle a steel spring made and applied in the manner hereinafter described. The steel should be carefully drawn out to a small rod (or wire) of about one eighth of an inch thick & about five feet in length, it can be drawn out either by a hammer or a wire plate; they are best to be drawn out with a hammer, as by hammering, the pores of the steel are closed, and the flaws are all worked out, otherwise if drawn out by a wire plate, the pores of the steel are left open, and oftentimes flabby. A space of two or three inches in the middle of the rod should be left somewhat thicker than the other part, for the purpose of receiving the webbing.

Then form it into a scroll by closely wrapping it around a rod of the size of about five eighths of an inch in width and three eighths of an inch in thickness, beginning to wrap at each side of the centre, leaving sufficient room in the centre of the spring to receive the webbing of full width.

This spring when wrapped should be heated to a blood red heat, to prevent it from breaking or cracking, while bending. The ends of the spring which go under the cap plate, of the head of the saddle tree, should be made flat & punched for the purpose of riveting it fast on the head of the tree and left sufficiently strong that when riveted to the tree it should not break.

The spring when thus made should be properly tempered so as to preserve and

7040 X

retain its elasticity, and prevent it from breaking, it should then be fastened to the tree by placing the ends of the spring under the cap plate over the head of the tree without binding them firmly together with the flat surface of the horn, upwards —

The webbing is fastened to the castle in the usual manner, and attached to the back part of the spring (instead of being tucked on the head of the saddle as is the usual mode.) When the webbing is fastened and strained the spring, always has an inclination upwards, keeping the seat always neat and in its proper shape, which gives a light elastic motion to the rider, and consequently does not come down in that dead heavy manner of a saddle made in the usual way, whereon horses are liable to injury, by being rode with a saddle constructed in this way, than in the usual way — saddles made in this plan do not differ in appearance from the neatest plain or quilted saddles. — The advantages that this improvement posesses, over Morris' and all others which have come under my notice are, that the tree is left perfect and whole as in common saddles, thereby being less liable to break, a very prominent objection to all others that I have ever seen — — —

The spring is made elastic because of the length of the horn, more durable on account of its particular shape and situation, it being placed in that part of the saddle which preserves and prevents it from being in any way injured or otherwise strained, giving the greatest possible ease and comfort to both the rider and horse.

In testimony that the above is a true specification of my said improvement as above described, I have hereunto set my hand this 14th day of March 1832.

Witness,

Benjamin Stent
A. Kimball
